Primary Examiner — Darlington Ly(74) *Attorney, Agent, or Firm* — McCoy Russell LLP(57) **CLAIM**

The ornamental design for an expandable collet body, as shown and described.

DESCRIPTION

FIG. 1 is a perspective view of an expandable collet body of a single sided fastening system showing my new design;
FIG. 2 is a front elevation view thereof;
FIG. 3 is a top plan view thereof; and,
FIG. 4 is a bottom plan view thereof.
The broken lines in the drawings illustrate portions of the expandable collet body that form no part of the claimed design.
